ATTORNEY.

UNITED STATES PATENT OFFICE.

WILLIAM A. WRIGHT, OF CENTRETON, NEW JERSEY, ASSIGNOR OF ONE-THIRD TO LAFAYETTE PALMER, OF HARRISBURG, PENNSYLVANIA.

COMBINED ENVELOPE, LETTER-SHEET, CIRCULAR, AND CASING.

SPECIFICATION forming part of Letters Patent No. 521,902, dated June 26, 1894.

Application filed June 15, 1893. Serial No. 477,649. (No model.)

To all whom it may concern:

Be it known that I, WILLIAM A. WRIGHT, a citizen of the United States, residing at Centreton, in the county of Burlington, State of New Jersey, have invented a new and useful Improvement in a Combined Envelope, Letter-Sheet, Circular, and Casing, which improvement is fully set forth in the following specification and accompanying drawings.

My invention consists of a combined envelope, letter sheet, circular and casing, the same being formed of one piece of material, as will be hereinafter set forth and claimed.

Figure 1 represents a perspective view of an envelope and letter sheet, in open condition, embodying my invention. Fig. 2 represents a perspective view of the same in closed condition. Fig. 3 represents a perspective view, when the sheet is employed as a circular. Fig. 4 represents a perspective view when the parts are converted into a casing or bag.

Similar letters of reference indicate corresponding parts in the several figures.

Referring to the drawings: A designates a combined envelope, letter sheet, circular and casing, formed of the sheet folds B, C and D, the separate side flaps E, F, and E', F', and the end flap G.

At suitable points mucilage or other adhesive material is applied, whereby the flaps may be sealed. Perforations are made in the flaps where the mucilage exists, so that when the envelope is to be opened, the paper or material may be cut or torn at the perforations, thus providing convenient means for such opening, without injuring the sheet folds B, C, and D.

The operation is as follows: When a letter sheet and envelope are required, the parts B and C are folded, and the adhesive material of the side flaps E', F', is moistened and pressed against the fold C. The adhesive

material of the end flap G is also moistened, and then pressed against said fold C, and the side flaps E and F, whereby the parts are sealed and the letter sheet is inclosed by the envelope, as produced. The folds E', F', now close the sides of the folds B, C, D, which otherwise would be open, and prevent the contents of the letter to be read from without. When a circular is required in lieu of a letter-sheet, the end flap G is caused to adhere to the side flaps E and F, whereby a pocket is formed. The folds B and C which are part of a circular, are then slipped into said pocket without being sealed. The flaps E', F', may be inserted between the folds B and C, leaving the sides of the latter open, as shown in Fig. 3, to be in accord with postal regulations. Again the end flap G and side flaps F, F' may be secured by the mucilage to the fold C, leaving the folds E, E', open, thus producing a casing into which papers, cards, &c., may be inserted, and afterward closed by said folds E, E', see Fig. 4.

Having thus described my invention, what I claim as new, and desire to secure by Letters Patent, is—

1. The folds B, C, and D, the separate flaps E, F, and E', F', on the sides of the fold D, and the flap G on the end of said fold D, the flaps G and E', F', having adhesive material thereon, substantially as described.

2. The folds B, C, and D, the flaps E, E', F, F', and the flap G on the end of said fold D, the flaps G, E', and F' having adhesive material thereon, and perforated at the place of occupation of said material, substantially as described.

WILLIAM A. WRIGHT.
